California

Application June 21, 1954, Serial No. 31,078

Term of patent 7 years

(Cl. D74—17)

To all whom it may concern:

Be it known that I, Jerome P. Vogel, a citizen of the United States, residing at Hollywood, county of Los Angeles, and State of California, have invented a new, original, and ornamental Design for a Ball Type Writing Instrument, of which the following is a specification, reference being had to the accompanying drawing, forming a part thereof.

Fig. 1 is a perspective view of a ball type writing instrument, showing my new design.

Fig. 2 is a front elevational view thereof, and

Fig. 3 is an end view thereof.

The contrasting band shown in Figs. 1 and 2 of the drawing extends completely around the barrel, the back of the barrel being otherwise plain and unornamented.

I claim:

The ornamental design for a ball type writing instrument, substantially as shown and described.
